(57) **CLAIM**

The ornamental design for a suture needle having a rotatable joint, as shown and described.

DESCRIPTION

FIG. 1 is a perspective view of a suture needle having a rotatable joint, showing our new design;

FIG. 2 is a left side view of the suture needle shown in FIG. 1;

FIG. 3 is a right side view of the suture needle shown in FIG. 1;

FIG. 4 is a proximal end view of the suture needle shown in FIG. 1;

FIG. 5 is a distal end view of the suture needle shown in FIG. 1;

FIG. 6 is a top plan view of the suture needle shown in FIG. 1;

FIG. 7 is a bottom view of the suture needle shown in FIG. 1;

FIG. 8 is a perspective view of a suture needle having a rotatable joint, showing another embodiment of our new design;

FIG. 9 is a left side view of the suture needle shown in FIG. 8;

FIG. 10 is a right side view of the suture needle shown in FIG. 8;

FIG. 11 is a proximal end view of the suture needle shown in FIG. 8;

FIG. 12 is a distal end view of the suture needle shown in FIG. 8;

FIG. 13 is a top plan view of the suture needle shown in FIG. 8; and,

FIG. 14 is a bottom view of the suture needle shown in FIG. 8.

The dash-dot-dash type broken lines define the boundaries of the claimed design. The dash-dash-dash-dash type broken

(Continued)

lines in the drawings depict portions of the suture needle having a rotatable joint and form no part of the claimed design.
